UNITED STATES PATENT OFFICE.

HENRY L. WALLACE, OF WALLINGFORD, CONNECTICUT, ASSIGNOR TO
R. WALLACE & SONS MFG. CO., OF WALLINGFORD, CONNECTICUT;
A CORPORATION.

DESIGN FOR A HANDLE FOR SPOONS, FORKS, OR SIMILAR ARTICLES.

SPECIFICATION forming part of Design No. 35,647, dated February 4, 1902.

Application filed December 12, 1901. Serial No. 85,705. Term of patent 7 years.

To all whom it may concern:

Be it known that I, HENRY L. WALLACE, of Wallingford, in the county of New Haven and State of Connecticut, have invented a new and useful Design for a Handle for a Spoon, Fork, or Similar Article; and I do hereby declare the following, when taken in connection with the accompanying drawing and the letters of reference marked thereon, to be a full, clear, and exact description of the same, and which said drawing constitutes part of this specification, and represents a face view of a handle for a spoon, fork, or similar article embodying my design.

This invention relates to a handle for a spoon, fork, or similar article; and it consists in the configuration and ornamentation as hereinafter shown and described in the accompanying illustration.

At the outer end of the handle is an elaborate tip A, surmounted by floriated scrolls B, which border a name or letter panel C. Between the panel C and the inner end of the spoon are series of scrolls D, E, F, and G, the inner ends of the scrolls G rolling inward and meeting reversibly-turned scrolls H.

Having fully described my invention, what I claim as new, and desire to secure by Letters Patent, is—

The design for a handle for a spoon, fork or similar article as herein shown and described.

In testimony whereof I have signed this specification in the presence of two subscribing witnesses.

HENRY L. WALLACE.
